United States Patent Office

Des. 197,481
Patented Feb. 11, 1964

197,481

TISSUE HOLDER

Bertrand N. Trombley, Bloomfield Hills, Mich. (6% Harper P. Ransbury Co., Inc., 1234 Barth Ave., Indianapolis, Ind.)

Filed July 2, 1963, Ser. No. 75,627

Term of patent 14 years

(Cl. D52—2)

*FIG. 4.FIG. 5.FIG. 6.*FIG. 1 is a front elevational view of a tissue holder embodying my new design, the rear being substantially the same as the front shown;

FIG. 2 is a top plan view thereof;

FIG. 3 is an elevational view taken from one end thereof, the other end being essentially the same as the end shown;

FIG. 4 is a bottom plan view thereof;

FIG. 5 is a vertical section taken on the line 5-5 of FIG. 3; and

FIG. 6 is a vertical section taken on the line 6-6 of FIG. 1.

I claim:

The ornamental design for a tissue holder, as shown and described.
